United States Patent Office

Des. 195,350
Patented June 4, 1963

195,350

WALL LIGHT

Alexander Simkins, 221 Linden Blvd., Brooklyn, N.Y.

Filed May 16, 1962, Ser. No. 70,173

Term of patent 14 years

(Cl. D48—4)

FIG. 1 is a front elevational view of the wall light showing my new design;

FIG. 2 is a side elevational view thereof; and

FIG. 3 is a top plan view thereof.

The rear, not shown, is substantially plain as indicated in FIGS. 2 and 3.

I claim:

The ornamental design for a wall light, as shown and described.
